Patented Sept. 28, 1976

241,639

COMBINATION FISHING ROD HANDLE AND RADIO

John A. Francis, 3720 Morgan Drive,
Weirton, W. Va. 26062

Filed Apr. 8, 1975, Ser. No. 567,143

Term of patent 14 years

Int. Cl. D22—05

FIG. 1

FIG. 2

FIG. 3

FIG. 4

FIG. 5

FIG. 1 is a top plan view of a combination fishing rod handle and radio according to my new design;

FIG. 2 is a side elevation view of the design shown in FIG. 1;

FIG. 3 is a bottom view of the design shown in FIGS. 1 and 2;

FIG. 4 is a rear view of the design shown in FIG. 3; and

FIG. 5 is a front view of the design shown in FIG. 3.

I claim:

The ornamental design for a combination fishing rod handle and radio, as shown.
